(57) **CLAIM**

The ornamental design for a sliding hanger holder, as shown and described.

DESCRIPTION

FIG. 1 is a perspective view of a sliding hanger holder showing our new design;

FIG. 2 is a front elevational view thereof;

FIG. 3 is a rear elevational view thereof;

FIG. 4 is a side elevational view thereof;

FIG. 5 is a top plan view thereof;

FIG. 6 is a bottom plan view thereof; and,

FIG. 7 is a perspective view of the sliding hanger holder of FIG. 1 with the hanger arm in a vertically extending storage position.

The broken lines shown in the drawing disclosure are for illustrative purposes only and form no part of the claimed design.
